(57) **CLAIM**

The ornamental design for a “monolithic rider arch for glass furance regenerator,” as shown and described.

DESCRIPTION

FIG. 1 is a perspective view of a monolithic rider arch for glass furance regenerator which embodies our new and original design therefore;

FIG. 2 is a front elevation view of thereof;

FIG. 3 is a rear elevation view of thereof;

FIG. 4 is a top plan view thereof;

FIG. 5 is a bottom plan view thereof;

FIG. 6 is a right side elevation view thereof; and,

FIG. 7 is a left side elevation view thereof.

The broken lines in the Figures represent structural elements in the environment of the claimed design, but which do not form part of the claimed design.
